APPARATUS FOR BANDING BOXES

Bror Anders Emil Johnson, Alsten, Sweden, assignor to Aktiebolaget Gerh. Archns, Mekaniska Verkstad, Stockholm, Sweden, a corporation of Sweden

Application June 25, 1934, Serial No. 732,319
In Sweden July 1, 1933

9 Claims. (Cl. 216—53)

This invention relates to an improved apparatus for applying pasted strips, labels or the like to boxes, packings or the like for instance match boxes or cigarette packings.

5 One object of my invention is to safely secure such strips etc. to boxes etc. even though the strip is not completely pasted.

Another object of my invention is to provide a 10 particularly smooth attachment of the strip to an underlying surface.

Still another object of my invention is to obtain a safe attachment of the strip to an underlying surface and nevertheless save a considerable amount of paste.

15 Thus it is also the object of this invention to remove certain inconveniences affecting certain strip-sealings. Such sealing may for instance be effected on drawing by means of a pincher a strip from a pile in a magazine, over a pasting device and supplying it to a box to be sealed. In such case one end of the strip is seized by a pincher or the like. The strip edge covered by the pincher is incompletely or not at all pasted and if said edge is by means of a stamp

20 pressed against a box side the paste adhering to the middle portion of the strip will not be squeezed out to said edge which will then not adhere to said box side. Nor will a sufficiently smooth affixing of the strip be obtained. Ac-

25 cording to the invention however the entire strip is safely secured to an underlying surface and the outer surface of the strip applied will have a very smooth surface well adapted for subsequent stamping. By this invention it is possible to spread out by squeezing the adhesive to a very thin layer. Thus a comparatively thick layer 30 of paste may be applied to a middle portion of the strip and nevertheless the subsequent operation will effect a paste layer much thinner than can be obtained by pasting the entire surface of the strip.

With these and other objects not specifically mentioned in view, the invention consists in certain new constructions and combinations 35 which will be hereinafter fully described and then specifically set forth in the claims hereunto appended.

In the drawings:

Fig. 1 is a side view of the apparatus embodying 40 the invention;

Fig. 2 is a front view of the apparatus; and

Figs. 3-5 illustrate various steps of a banding operation.

55 Referring now to the drawings the box to be sealed rests in an inclined position in a chute 2,

so that its front side 3 occupies a higher position than its rear side. In front of the box side 3 there is provided a magazine 4 for strips and a paste supply 5 having a perforated pasting pad 6. Above the box 1 a pincher 7 is movable towards and from the pasting pad. The pincher is connected to a swinging arm 8 fulcrumed on a shaft 9 in the machine frame 10 and carries a roller 11, which is by a tension spring 12 pressed against the periphery of a cam 13. The cam 13 is secured to a continuously rotating driving shaft 14.

An arm 15 actuated by a tension spring 16 is secured to a swinging shaft 16 in the frame 10 and supports the smoothing members. Another arm 17 is rigidly secured to the shaft 16 and supports a roller 19 which is by the spring 18 forced against the periphery of a cam 20 secured to the shaft 14. The arm 15 carries a pin 23 to which are pivoted two arms 21 and 22 respectively. The arm 21 constitutes together with another arm 23 having a roller 29 a double-armed lever. The roller is by means of a tension spring 30 forced against the periphery of a cam 31 which is secured to the shaft 14. The arm 22 forms together with another arm 24 having a roller 25 a double-armed lever. The roller 25 is by means of a tension spring 26 forced against the periphery of a cam 27 which is secured to the shaft 14.

30 The end of the arm 22 supports an adjustable finger 34 which is provided with a roller 36 journalled on a link 35 on the finger 34. The link is adjustable to occupy different angular positions. The finger 34 is held by a spring 37 in a definite 35 angular position relative to the arm 22 whereby said spring forces an abutment 38 on said arm against a set-screw 39 in the arm 22. Thus the finger 34 may yield upwards in a direction from the box 1. The arm 21 carries a link 33 which is 40 adjustable to occupy different angular positions and provided with a roller 32.

The applying of strips is effected by means of the apparatus described in the following manner. A strip 40 from the magazine 4 is on the pasting 45 pad 6 supplied with paste only at its middle portion. Thereafter the pincher 7 fetches the strip seizing it at its right hand edge which has not been pasted. The strip is moved by the pincher into the position above the box 1 shown in Fig. 3. 50 Thereafter the arm 15 moves the smoothing mechanism downwards, so that the roller 32 will primarily engage the strip near the upper edge of the inclined box side 3, whereafter it is lowered further until the rollers have reached the posi- 55

tion shown in Fig. 4. Then the roller 36 will engage the strip on the upper side of the box in the proximity of the upper edge of the box. At this moment the cam 37 will permit the spring 5 26 to swing the arm 22 towards the box 1 on further descending of the arms 21 and 22 and the pincher 7 releases the strip. Then the roller 32 continues smoothing out an end of the strip about the box side 3. Thereby the finger 34 yields so 10 that the roller 36 will continuously and with a somewhat increasing pressure press upon the strip end which is smoothed out about the upper box side, by moving the roller 36 along said side. Obviously the strip is thereby straightened so that it 15 will cover both box sides very smoothly and furthermore be correctly bent over the upper front edge of the box to obtain the position shown in Fig. 5. The result now referred to is obtained by moving the rollers 32 and 36 on descending the 20 arm 15 towards said front edge in an oblique direction relative to each box side i. e. not parallelly with anyone of them. Owing to the fact that the roller 32 will hit the strip on the box side 3 in an oblique direction close by said front edge, the 25 part of the strip that covers the box side close by said edge will be safely applied and adhere to the front box side even though said side would be bulged inwards, which latter will often occur. This improved effect will of course also be ob- 30 tained at the upper box side.

The scope of my invention should not be limited to the precise details thereof now described and illustrated in the drawings. Thus any member for the same purpose may be substituted for 35 the smoothing rollers. The strip etc. may be applied to a single surface or to any number of surfaces of a box etc. The strip etc. may be supplied to the box etc. in any way. However the transferring of the strip to the box in the manner above described is particularly convenient for 40 subsequent applying of the strip according to my invention.

I claim:

1. In an apparatus for banding boxes or the like, a smoothing out member, a box holder, and mechanism for moving said member towards a side of a box supported by said holder in a direction oblique to the plane of said side and for shifting said member to move on said box side 45 engaging a strip on said box side.
2. In an apparatus for banding boxes or the like, a smoothing out member, a box holder, and mechanism for moving said member towards a side of a box supported by said holder in a direction oblique to the plane of said side and for shifting said member to move on said box side engaging a strip on said box side, said member being mounted to yield away from said box side. 55
3. In an apparatus for banding boxes or the like, a pair of smoothing out members, a box holder, and mechanism for moving said members towards two adjacent sides of a box supported by said holder in directions oblique to the respective box sides to engage a strip on opposite 60 sides of an edge between said box sides and for

shifting said members to move apart on said sides.

4. In an apparatus for banding boxes or the like, a pair of smoothing out members, a box holder, and mechanism for moving said members towards two adjacent sides of a box supported by said holder in directions oblique to the respective box sides to engage a strip on opposite sides of an edge between said box sides and for shifting said members to move apart on said sides, said mechanism being arranged to move said members 10 to engage the two box sides one sequently to the other. 15

5. In an apparatus for banding boxes or the like, a pair of smoothing out members, a box holder, and mechanism for moving said members towards two adjacent sides of a box supported by said holder in directions oblique to the respective box sides to engage a strip on opposite sides of and in the proximity of an edge between said box sides and for shifting said members to move 20 apart on said sides. 25

6. In an apparatus for banding boxes or the like, a smoothing out member, a box holder, a pincher, mechanism for moving said pincher to draw a strip into position above a box supported by said holder, and mechanism for moving said member in an oblique direction towards said box into a position in front of said pincher and for shifting said member to move on a box side 30 towards said pincher. 35

7. In an apparatus for banding boxes or the like, a smoothing out member, a box holder, a pincher mechanism for moving said pincher to draw a strip towards a side of a box supported by said holder in a direction oblique to the plane of said side and further into position above an adjacent box side, and mechanism for moving said member in an oblique direction towards said box into a position in front of said pincher and for shifting said member to move on said adjacent 40 box side towards said pincher. 45

8. In an apparatus for banding boxes or the like, a smoothing out member, a paste supplier, a box holder, a pincher, mechanism for moving said pincher to draw a strip over said paste supplier to paste the under side of said strip and further into position above a box supported by said holder, and mechanism for moving said member in an oblique direction towards said box into a position in front of said pincher and for shifting said member to move on a box side towards 50 said pincher. 55

9. In an apparatus for banding boxes or the like, a smoothing out member, a strip supplier, a paste supplier, a box holder, a pincher, mechanism for moving said pincher to draw a strip from said strip supplier over said paste supplier to paste the under side of said strip and further into position above a box supported by said holder, and mechanism for moving said member in an oblique direction towards said box into a position in front of said pincher and for shifting said member to move on a box side towards said pincher. 60

BROR ANDERS EMIL JOHNSON.
